US0D1037044S

(12) **United States Design Patent** (10) **Patent No.:** **US D1,037,044 S**
(45) **Date of Patent:** **** Jul. 30, 2024**

(54) **DOORBELL**

(71) Applicant: **Shenzhen Oceanwing Smart Innovations Technology Co., Ltd,**
Shenzhen (CN)

(72) Inventors: **Chenyu Zhang**, Shenzhen (CN);
Yingpeng Li, Shenzhen (CN); **Jihui Lai**, Shenzhen (CN)

(73) Assignee: **Shenzhen Oceanwing Smart Innovations Technology Co., Ltd,**
Shenzhen (CN)

(**) Term: **15 Years**

(21) Appl. No.: **29/815,366**

(22) Filed: **Nov. 12, 2021**

(30) **Foreign Application Priority Data**

Jun. 17, 2021 (CN) 202130374067.2

(51) **LOC (14) Cl.** **10-05**

(52) **U.S. Cl.**

USPC **D10/118.2**; D10/118

(57) **CLAIM**

The ornamental design for a doorbell, as shown and described.

DESCRIPTION

FIG. 1 is a front perspective view of a doorbell showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 of FIG. 3.

The broken lines depicting the remainder of the doorbell form no part of the claimed design.

1 Claim, 8 Drawing Sheets
